UNITED STATES PATENT OFFICE.

ARNOLD W. ZIMMERMAN, OF CHICAGO, ILLINOIS, ASSIGNOR OF ONE-HALF TO PETER M. KLING, OF ELIZABETH, NEW JERSEY.

LOCK FOR VESTIBULE-CAR DOORS.

SPECIFICATION forming part of Letters Patent No. 775,617, dated November 22, 1904.

Application filed July 7, 1904. Serial No. 216,616. (No model.)

To all whom it may concern:

Be it known that I, ARNOLD W. ZIMMERMAN, a citizen of the United States, residing at Chicago, in the county of Cook and State 5 of Illinois, have invented certain new and useful Improvements in Locks for Vestibule-Car Doors, of which the following is a specification.

Vestibule-car doors are now constructed of 10 two or more panels or sections hinged together so as to fold compactly one upon another when the door is opened and thrown back against the end of the car. With this form of door considerable difficulty has been encountered 15 in providing a suitable locking mechanism which can be conveniently operated either from the inside or from the outside of the car. The locking mechanism which is usually employed on this form of vestibule-door has been 20 applied to the far edge of the outer section of the door farthest from the hinged connection of the sectional door with the door-frame and has been of such construction that it is necessary to firmly press the hinged center of the 25 sectional door into position in the door-frame before the lock will engage its keeper. In this structure, which is usually employed, it has also been found necessary to provide an auxiliary lock or catch adjacent to the central 30 hinge, (which connects the two sections of the door,) so as to engage the door-frame and hold the door firmly in closed position.

The present invention consists in providing 35 a sectional door with a locking mechanism arranged upon one of the door-sections adjacent to the line of the central hinges which connect the panels or sections and adapted to engage the door-frame at both top and bottom and provided with a convenient operating handle 40 or knob by which the door can be conveniently and firmly pressed into closed position in the door-frame and the locking mechanism operated for securely holding the door closed. The operating handle or knob is preferably 45 extended through the door-section on which it is mounted, so that the locking mechanism may also be operated from the outside of the car. The lock proper consists, preferably, of two longitudinally - movable bars mounted

upon the door so that their upper and lower 50 ends may be projected, respectively, beyond the upper and lower edges of the door and having suitable means operated by the door knob or handle for simultaneously throwing said parts in opposite directions to engage in suitable sockets or keepers formed in the top and bottom of the door-frame. This locking mechanism is also adapted to hold the sectional door in open folded position by engaging 55 similar sockets, one of which is supported 60 upon a bracket secured to the end of the car-body, while the other is set into the vestibule-floor.

In order that my invention may be fully understood, I will first describe the same with 65 reference to the accompanying drawings and afterward point out the novelty more particularly in the annexed claims.

In said drawings, Figure 1 is a detail side elevation of one end of a vestibule-car, showing the near side of the vestibule broken away for the purpose of clearly illustrating the inner side of the opposite door with my improved locking mechanism applied thereto. Fig. 2 is a detail vertical sectional view showing the improved lock mechanism for the sectional vestibule-door. Fig. 3 is a detail horizontal sectional view showing the door in closed position. Fig. 4 is a similar view showing the door locked in open position. Fig. 5 75 is a detail front view of the main operating mechanism of the lock. Fig. 6 is a front view of a novel form of hinge used in connection with the locking mechanism for hinging the 80 two sections of the door.

1 is a vestibule-car of any suitable construction, and 2 is the vestibule having the usual door-openings 3 at the opposite sides, which lead to the steps 4. Each of the door-openings 3 is closed by the sectional door, made up, 90 preferably, of two panels or sections 5 and 6, which are hinged together at 7. The section 5 is hinged to the door-frame at 8 to form a hinge-support for the sectional door.

The section or panel 6 of the double door is 95 provided with a locking mechanism, its rear edge adjacent to the central line of hinges 7. This locking mechanism consists, preferably,

of two oppositely-locking bolts or bars 10 and 11, adapted to be projected beyond the upper and lower ends, respectively, of the door to engage the upper socket or keeper 12, mounted at the upper edge of the door-frame 3, and the lower socket 13, cut into the threshold plate or floor of the vestibule. The locking-bars 10 and 11 are formed with beveled-out ends, as shown at 10^a and 11^a, to enable them to force the door into closed position by wedging into their sockets. The bars 10 and 11 are suitably supported upon the door-section in vertical position. The inner adjacent ends of the locking-bolts 10 and 11 slide in a suitable 15 casing 15. Each of the bolts is formed at its inner end with a rack-bar 16, meshing with the rotatable pinion 17, mounted upon the arbor 18, which is journaled in bearings 19, formed in the casing 15 and removable lock-plate 15^a. The arbor 18 has hinged to its inner end a handle-loop 20, by which the pinion 17 may be rotated from the inside of the car. 25 is a countersunk plate set into the outer part of the door-section 6, and 26 is a handle 25 suitably mounted in the countersunk plate 25 and carrying the inwardly-projected squared key or axle 27, which fits in the socket 28, formed in the arbor 18 of the pinion 17. Any suitable means may be provided for holding 30 the handle 26 in position in the countersunk plate 25. I prefer to screw-thread the hub of handle 26, as shown at 26^a, and thread the opening through countersunk plate 25 for the reception of the threaded hub. When the 35 parts are assembled, the hub of handle is screwed into the threaded opening of plate 25 just far enough to insure its being held in place, sufficient leeway being allowed for the partial rotation of the handle for operating 40 the lock. The plate is then screwed in position on the door, with the squared axle engaging socket 28 of arbor 18.

It will be observed by referring to Fig. 6 of the drawings that the countersunk plate 25 is 45 one of a pair of central hinged plates constituting one of hinges 7 for connecting the sections 5 and 6 of the door. The other hinge-plate connected with plate 25 (shown at 30) is countersunk into the outer face of the section 50 5 of the door, so that when the door is opened and the two sections are folded together the handle 26 will fit into the cup or socket of plate 30 and allow the two sections of the door to fold closely together, as shown in Fig. 4.

55 When the door is opened and folded back against the end of the car, the locking mechanism is operated to cause the upper and lower bolts to engage sockets at top and bottom for securing the door in opened folded position. 60 It will be observed that by reason of the construction and location of the locking mechanism adjacent to the central hinge of the door-sections it is a simple matter to force the door into closed position and securely lock it by a 65 single operation.

It will be observed by referring to Fig. 3 of the drawings that the free end of outer section 6 of the door fits into a mortise in the door-frame and that the hinged central edges of the door-sections are chamfered to fit snugly together. 70

The object of my improved locking mechanism will be clear. When the door is closed, pressure is applied upon the handle to force the door to its seat and the handle turned for 75 throwing the bolts into their sockets. The beveled ends of the bolts force the door snugly to its seat. As already explained, the door may be opened and closed from the inside or outside. 80

While I have illustrated and described the central hinge connecting the two sections or panels of the door as formed of two countersunk and socketed plates or leaves and a countersunk handle journaled in one of these 85 socketed plates or leaves, I would have it understood that the essence of this part of my invention is a socketed hinge plate or leaf 30, the socket of which is adapted to receive the operating-handle. The plate 25 is preferably, 90 also, formed with a socket or cup to adapt it to use with a mortised handle; but this plate 25 may be a simple flat plate or leaf, and the operating-handle may be of any of the usual or ordinary forms. 95

Having thus described my invention, the following is what I claim as new therein and desire to secure by Letters Patent:

1. The combination of a door-frame, with a sectional door hinged therein and comprising sections or panels which are hinged together, a locking mechanism comprising a pair of oppositely-moving bolts mounted upon one of the door-sections adjacent to the line of connecting-hinges and extending vertically 100 upon the door, and an operating-handle located upon said door-section and having means for engaging said bolts for simultaneously operating them, substantially as set forth. 105

2. In a vestibule-car, the combination of a 110 vestibule-door frame, a sectional door hinged therein, oppositely-moving locking-bolts mounted upon one of said door-sections, hand-operated means for operating said bolts, locking-sockets in the top and bottom of the door-frame adapted to receive said bolts, and additional top and bottom locking-sockets mounted respectively on the end of the car-body and in the vestibule-floor in position to receive said bolts when the sectional door is 115 folded back into open position, substantially as set forth. 120

3. The combination of a door-frame, with a door hinged therein, a locking-bolt movably mounted upon the door, a rotatable arbor or axle in the door operatively connected with said bolt, a countersunk plate secured to one face of the door, a rotatable handle having threaded connection with said countersunk plate and a squared axle projecting from said 125 130

handle into said rotatable arbor or axle, substantially as set forth.

4. The combination of a door-frame, with a sectional door hinged therein and comprising sections or panels which are hinged together, and a locking device mounted upon one of the door-sections and including a rotatable operating-handle, one of the hinges connecting the door sections or panels being formed with a socketed plate or leaf, the socket of which is adapted to receive said operating-handle when the sectional door is folded back into open position, substantially as set forth.

5. The combination of a door-frame, with a sectional door hinged therein and comprising

two sections connected by a central line of hinges, one of said hinges consisting of a pair of countersunk plates formed with sockets and secured respectively to the adjacent edges of said door-sections, a locking-bolt 20 mounted upon the door, a rotatable operating arbor or axle having means for actuating said bolt, and a rotatable handle journaled in one of said countersunk plates and engaging said rotatable arbor or axle, substantially as set 25 forth.

ARNOLD W. ZIMMERMAN.
